CONTAINER WITH WINDOW

Matthew C. Ricciardi, Phillipsburg, N. J., assignor to The Canister Company, Inc., Phillipsburg, N. J., a corporation of New Jersey

Application July 25, 1947, Serial No. 763,698

1 Claim. (Cl. 206—45.31)

1

My invention relates to containers, and more particularly to fibrous containers having a window or other viewing means embodied therein.

It has not been usual to provide windows for containers formed from fibrous or other similar material because of the high cost factor involved. Heretofore various solutions to this problem such as adhesively bonding a strip of transparent material over an opening cut in the side wall of such container have been devised. These solutions have been found unsatisfactory due to the fact that the bonding agent would become ineffective when dried out or subjected to heat, an excessive amount of transparent material had to be used, and the window generally was easily subject to displacement.

My invention overcomes these defects by providing a window which utilizes a minimum of material, is easy to position on the container, and which is firmly secured against displacement without the use of any bonding agent. This is achieved by using a new and novel retaining member which may be quickly fashioned from ordinary inexpensive thin gauge sheet metal or other similar material.

An object of my invention is to provide a fiberboard container having a new and improved window member.

Another object of my invention is to provide such a window which is secured to the container by a new and improved frame.

These and other objects and features of my invention may be readily seen from the following description thereof in which reference is made to the figures of the accompanying drawings.

In the drawings:

Fig. 1 is a perspective view of a container having a window embodying the features of my invention positioned in the side wall thereof;

Fig. 2 is a perspective view of a window and retaining member embodying the features of my invention;

Fig. 3 is a perspective of a portion of the container shown in Fig. 1 showing the window in section; and

Fig. 4 is a side view of a portion of a container having the window member removed.

As shown in Fig. 1 a container embodying my invention comprises a body portion 2 of generally rectangular shape and made from any suitable cheap material such as fiberboard and cover members 4 and 6 preferably stamped from some suitable inexpensive sheet metal, secured to the opposite ends of the body portion by crimping

2

portions 8 and 10 around the edges thereof. A window assembly 12 is positioned in the side wall 14 of the container.

The window assembly 12 is composed of a sheet 5 of transparent material 16 secured in a frame 18 formed from any suitable material such as inexpensive thin gauge sheet metal. The frame member 18 may be made by a single stamping, and is preferably a unitary strip. Projecting 10 means 22 for securing the frame 18 to the opening 20 cut in the side wall 14 of a container are integrally secured to and extend from said frame at suitable intervals therearound. The projecting means 22 are keyed so as to fit into 15 the slots or recesses 24 formed around the edge of the opening 20 when the frame 18 is properly positioned therein. A flange 26 extends around the periphery of the frame 18 at substantially right angles thereto and serves as an 20 abutting member for the transparent sheet 16. The projections 22 are formed with portions 28 bowed slightly inward toward the frame 18 to retain the transparent sheet 16 more or less 25 fixedly in the frame. Thus the transparent sheet which is preferably cut from flexible material such as cellophane and is of sufficient size to be retained within and abut against the flange 26 may be easily flexed downward and under the inwardly bowed portions of the projections 22 and so be retained thereby against the bottom portion 20 of the frame member.

In manufacturing the container the body portion 2 having the opening 20 with the slots or notches 24 positioned around the edge thereof is 30 formed in a conventional manner so that the opening 20 is located in one of the wider side walls. The window frame 18 having the projections 22 is then stamped out of sheet metal and the projections 22 are bowed inwardly from 35 the flange 26 and the extremities 32 thereof are somewhat angularly disposed outwardly as shown in Fig. 2. The transparent sheet 16 is then formed and positioned in the frame by flexing it downwardly past the bowed portion 28 so as to 40 be retained thereby in the frame.

After the window assembly 12 is assembled it 45 is positioned in the opening 20 so that the projections 22 fit into the slots or notches 24 and the angularly disposed extremities 32 thereof extend 50 outwardly over the portions of the side wall 14 adjacent said slots or notches. The projections may then be quickly and easily swedged against the side wall of the container by a die or other suitable tool. The flexible transparent window 55 is then fixedly secured between a portion of the

frame and portions of the side wall as well as being securely retained within the frame member 18.

Various other forms of my invention may readily be seen. Thus the size, the shape of the opening and the positioning thereof may be varied considerably. The example of my invention above shown and described is for illustrative purposes only and it is not intended that the scope of the following claim be limited thereby.

I claim:

A container comprising a body formed of fibrous material and having a window opening therein with positioning notches projecting outward from the opening at spaced points about the edges of the opening, a transparent member covering said opening and means for holding said transparent member in place with respect to said opening including a frame having a marginal portion overlying the edges of the transparent member, a flange extending substantially at right angles to said portion and engaged by the edges of said transparent member, said flange also en-

gaging the outer surface of said body about the edges of said opening and outside said positioning notches, tongues extending inward from said flange beneath said marginal portion of the frame and serving to hold the transparent member in place with respect to said frame, said tongues having reversely turned extensions located in said notches and projecting outward therefrom on the interior of said body and gripping the body to hold the frame in place thereon.

10 15 MATTHEW C. RICCIARDI.
